UNITED STATES PATENT OFFICE.

JOHN ROSE, OF PHILADELPHIA, PENNSYLVANIA, ASSIGNOR OF ONE-HALF
TO CHARLES F. DOLLNER, OF SAME PLACE.

UMBRELLA-RUNNER RETAINER.

SPECIFICATION forming part of Letters Patent No. 380,935, dated April 10, 1888.

Application filed November 7, 1887. Serial No. 254,527. (No model.)

To all whom it may concern:

Be it known that I, JOHN ROSE, a citizen of the United States, and a resident of Philadelphia, Pennsylvania, have invented certain Improvements in Umbrella-Runner Retainers, of which the following is a specification.

The object of my invention is to so construct a retainer for the runners of umbrellas or parasols that the same will be of an inexpensive character, and will not necessitate any expensive preparation of the stick for its reception. This object I attain in the manner hereinafter set forth, reference being had to the accompanying drawings, in which—

15 Figure 1 is a longitudinal section of part of an umbrella-stick with my improved runner-retainer applied thereto. Fig. 2 is a transverse section on the line 12, Fig. 1. Fig. 3 is a perspective view of the retainer detached from the stick; and Fig. 4 is a view similar to Fig. 2, but showing the retainer applied to a bamboo or other hollow stick.

A is the stick of the umbrella or parasol, in one side of which is formed a saw-kerf, *x*, for 25 the reception of the retainer, the latter consisting of a skeleton frame comprising a back bar, *a*, and a front bar, severed so as to form two projecting tongues, *b* and *d*, the whole being made in one piece. The back bar, *a*, of 30 the retainer is in the form of a segment of a circle and fits snugly to the base of the saw-kerf *x* in the stick, a lug, *f*, projecting outward from said back bar and receiving the transverse pin or rivet *g*, whereby the retainer is held in place in the stick. The 35 tongues *b* and *d* of the front bar of the retainer are flush with the face of the stick; but said tongue *b* has an enlargement, *i*, which serves as the stop for the retainer, the tongue *b* being 40 elastic and the enlargement *i* being beveled on one face, so that as the runner is moved past the same the tongue will be forced into the saw-kerf in the stick, and will spring outward therefrom when opportunity offers, the 45 lower end of the tongue *b* overlapping the tongue *d*, so as to limit its outward movement. That part of the back bar, *a*, which is between the upper end of the tongue *b* and the fastening-lug *f* is also free to yield when the 50 tongue *b* is depressed, so that its resiliency is added to that of the tongue, and the latter thus rendered extremely elastic.

My improved retainer is extremely simple in construction, and can at one stroke be punched out of a plate of sheet metal, while 55 the application of the retainer to the stick is an inexpensive operation, since the plain saw-kerf is the only recessing of the stick which is necessary, and the transverse drilling of the stick and the driving in of the pin serve to secure the retainer in place.

60 My improved retainer can be applied to bamboo or other hollow sticks, as well as to solid sticks, as will be evident on reference to Fig. 4.

65 I claim as my invention—

1. The combination of the stick of an umbrella with a runner-retainer having a front bar forming a spring-tongue and a back bar integral with said front bar and secured to the 70 stick midway, or thereabout, of its length, but otherwise free from connection with said stick, whereby the resiliency of the spring-tongue is supplemented by that of a portion of the back bar, all substantially as specified.

75 2. An umbrella-runner retainer having a front bar forming a spring-tongue, with enlargement projecting beyond the face of the same, and a segmental back bar integral with the front bar, and having a fastening-lug midway, or thereabout, of its length, that portion 80 of the back bar between the fastening-lug and the end of the spring-tongue being resilient, all substantially as specified.

85 3. The combination of the stick, having therein a saw-kerf with true segmental base, with a retainer having a front bar forming an elastic tongue, with inclined enlargement projecting beyond the face of the stick, and a resilient segmental back bar integral with said 90 front bar, and having a fastening-lug midway, or thereabout, of its length, but otherwise free from connection with the stick, all substantially as specified.

95 In testimony whereof I have signed my name to this specification in the presence of two subscribing witnesses.

JOHN ROSE.
